UNITED STATES PATENT OFFICE.

MICHAEL BOGRE, OF DETROIT, MICHIGAN.

WASHING-MACHINE.

1,373,792.

Specification of Letters Patent.

Patented Apr. 5, 1921.

Application filed March 13, 1920. Serial No. 365,549.

To all whom it may concern:

Be it known that I, MICHAEL BOGRE, a citizen of the present domain of Hungary, residing at Detroit, in the county of Wayne 5 and State of Michigan, have invented certain new and useful Improvements in Washing-Machines, of which the following is a specification, reference being had therein to the accompanying drawings.

10 This invention relates to improvements in washing machines, pertaining more particularly to machines of comparatively large capacity and designed for power operation.

The objects of the present invention are 15 to provide a construction which will accommodate a comparatively large amount of clothing or other materials to be washed, and permit the material being washed concurrently, and at the same time provide the 20 washing operation in such manner as to produce effective cleansing of the material being washed. A further object is to provide a construction in which the materials to be washed can be readily introduced into 25 position and removed after the washing has been completed while maintaining the rubbing elements in their approximate position.

A further object is to provide a construction which is simple and efficient in operation, durable in construction and which can 30 be manufactured and installed at a relatively low cost.

With these and other ends therefore, the 35 nature of which will be readily understood as the invention is hereinafter disclosed, said invention consists in the improved construction and combination of parts, hereinafter more fully described, illustrated in the accompanying drawings, and more particularly pointed out in the appended claims.

40 In the accompanying drawings in which similar reference characters indicate similar parts, in each of the views,

Figure 1 is a top plan view of a washing 45 machine according to one embodiment of the present invention, parts being broken away for the purpose of illustrating the construction;

Fig. 2 is a vertical, longitudinal sectional 50 view of the same;

Fig. 3 is a transverse sectional view of the same.

The present invention is in the form of 55 a container capable of being divided into a number of independent compartments by

the use of rubbing surfaces, each compartment being practically independent of each other so far as the possibility of distribution of material from one compartment to another is concerned, and at the same time, 60 the materials of each compartment are given a rubbing action such as to produce effective cleansing. The container is mounted in the casing which contains the washing fluid, in such manner as to permit the materials being washed to be introduced or removed while the rubbing surfaces are in position, this result being obtained by providing the material container with an open side, the removal of which exposes all of the 65 compartments at the same time, so that each compartment can be filled or emptied individually without disturbing the parts which themselves produce the washing action. At the same time, the rubbing action is provided 70 by rubbing surfaces which are movable relative to each other at opposite sides of the compartments, the result being that the material between any two rubbing surfaces is being continually rubbed and turned about 75 through the movements of the rubbing surfaces. Since the material container is located within the washing fluid, it will be readily understood that this turning and movement of material by the movements of 80 the rubbing surfaces will act to provide for proper distribution of the fluid through the materials in a compartment and at the same time so manipulate the materials as to insure bringing practically the entire portion 85 of the batch into proper position for rubbing action.

In the drawings, which illustrate one embodiment of the present invention, the fluid receiving casing is indicated at 10, this being shown as rectangular in contour and of suitable depth, and which may be mounted on feet 10^a or otherwise supported. The casing 10 is preferably provided with an open top—with the possible exception of a 90 portion 10^a presently described, the open top being closed during the washing operation by a suitable cover construction, this being shown in the present embodiment as in the form of two hinged covers 10^b and 10^c, 95 these covers being shown as hinged to the sides of the casing, the cover 10^c having a greater width than that section 10^b, this difference being provided to meet one of the conditions present; it will be understood, of 100 105 110

course, that other forms of covers may be employed, the invention not being limited in this respect.

Mounted within the casing 10 is a container 11 comprising end walls 11^a, the lower ends of which may rest upon the bottom of the container, and which may be continuous from side to side of the container or may be in the form of feet, as may be desired, the 10 perforated bottom 11^b located above and spaced from the bottom of the casing, a side 11^c and a side 11^d, these parts with the exception of side 11^d, being preferably secured together, in a manner to provide for a container 15 formation, side 11^d being removably secured in position by suitable means, such as latches 12. The sides 11^c and 11^d are preferably perforated.

The ends 11^a preferably carry rubbing 20 surfaces 13, which extend substantially throughout the vertical length of the container 11. And, if desired, such ends 11^a may project above the top plane of the casing to form supports for a crank shaft 14 25 presently described in detail. It will be understood, however, that the supports for such crank shaft may be independent of such ends if such construction be desired, the particular arrangement shown providing 30 for low cost of production.

In the embodiment shown, the container is designed to be divided into four compartments, this result being obtained by the use 35 of three independent rubbing surface carriers 15, 15^a and 15^b, these carriers having some of the general characteristics of the well known wash board, in that they are preferably arranged with rubbing surfaces operative on opposite sides of the carriers. 40 These carriers extend transversely of the direction of length of the container at spaced apart distances, three of these being shown, and since the carriers extend practically the full width of the container, the latter is 45 divided into four compartments, the outer compartment having as one wall an end 11^a and the other wall one of the carriers, while the two interior compartments have the opposite walls formed by carriers. The 50 carriers have a vertical length greater than the depth of the container, so that the upper end of the carrier is located above the top of the casing, while the lower end which passes through a slot in the bottom 11^c remains below the bottom of the container.

The carriers are adapted to be reciprocated vertically, the sides of the container having suitable guides within which the carriers travel, the upper ends of the carriers being connected to the crank portions 60 of crank shaft 14, the latter shaft being preferably arranged on what is generally known as the three-point form, this being preferred where the number of rubbing sur-

faces carriers is three or more, this arrangement serving to cause the carriers to reciprocate, but the arrangement is such that the time of commencement of the cyclical movement of one carrier differs from the time of commencement of the similar movement of an adjacent carrier, the result being that while all of the carriers are being moved by the rotation of the crank arm 14, the rubbing surfaces carried by the carriers have movements relative to each other, carriers 15 and 75 15^b being movable relative to the stationary surfaces 13 and movable relative to the surfaces of the carrier 15^a.

From the above, it will be clear that with a batch of material in each of the compartments rotation of the crankshaft will cause the three carriers to each provide for its independent cyclical movement with all of the carriers operating concurrently, and since the movements are in planes parallel to each other and to the end rubbing surfaces, there will be proper rubbing action provided in each compartment so as to effectively clean the materials within the compartment itself.

Crank shaft 14 may be rotated in any desired manner, the drawings showing the use of a small motor 16 mounted on cover section 10^d by a suitable chain connection or other form of drive. Since the materials to be washed are all located on the opposite side 95 of the end of the container from that of the motor, it will be readily understood that if desired, this particular cover section may be permanently secured to the casing, although it may be found desirable to provide for a removable connection such as would permit it to be removed at the time that it may be desired to remove the crank shaft and the rubbing surface carriers. This may be done at infrequent intervals, and hence 100 the arrangement may provide for such more or less permanency of position of this cover section.

As will be understood, the use of the four compartments each of which carries a 110 batch of material to be washed, provides for comparatively large capacity of machine so as to permit of a rather large quantity of material to be cleansed at each washing operation. This ability to provide for capacity through the particular form of the rubbing surface carriers has, of course, the disadvantage of requiring a comparatively 115 large container, bringing in the question of ability to readily insert and remove the material. This is met in the present embodiment by locating the container out of the geometrical center of the casing, and locating it closer to one side than to the other, locating the removable side 11^d on that side 120 of the container which is farthest removed from the side of the casing, which not only permits of ready removal of the side 11^d but

also enables the operator when the cover section 10^b has been opened so as to expose the interior, to readily reach into the end of each of the compartments which have been 5 opened by the removal of the side, to either position a new batch or remove a washed batch, the distance between the movable side and the side of the casing being such as to permit the clothes to be readily introduced 10 or removed from either of the compartments, the removal being toward the side of the casing at which the operator is standing and away from any possibility of the clothes being brought into contact with 15 either the crank shaft 14 or the connection between the crank shaft and the individual carriers.

This position of the container locates the 20 crank shaft to one side of the longitudinal center of the casing, as shown in Fig. 1, since it is desirable that the connections between the crank shaft and the carriers be located approximately the center of the latter in order that the carriers may reciprocate without undue difficulty. It is because 25 of this location that the cover sections are divided in the manner shown, the line of division being such as to permit each of the cover sections to be opened outward without difficulty. During washing operations both 30 covers are closed, and it may be necessary only to open cover 10^b in inserting or removing the materials to be washed.

It will be understood, of course, that the 35 container may be located at the geometrical center of the casing, in which case the spaces at the sides would be equal; since, however, the materials are to be inserted or removed only from one side, it is not necessary to 40 provide the same amount of space at the opposite side of the container, and for this reason I prefer to employ the general arrangement shown in the drawings.

The particular form which may be utilized 45 in producing the rubbing surfaces, may be varied to meet individual preferences, any of the well known forms being capable of being employed, the invention pertaining rather to the manner in which the surfaces 50 are moved relative to each other both in direction and the means employed, than to the particular form of the rubbing surfaces.

As will be understood, the crank shaft if 55 proper bearings are used, can be readily removed by an upward movement carrying the carriers from the container, it being understood that the connection with the motor will be made inactive, or the motor itself removed with the arrangement. This will 60 permit removal of the container itself bodily, should such action be found necessary. Since, however, the materials to be washed are wholly contained with the container itself, removal of the latter is not necessary, since the contents of the casing itself

being in liquid form, can be readily removed by a suitable drain cock.

As will be readily understood, the general construction is such as to provide for large capacity operations and is of such a character as to be simple and efficient in operation, durable in construction and capable of being manufactured at a comparatively small cost.

If desired a member 18 may be located below and preferably in alignment with removable side 11^a, this member being preferably perforated. This element acts as a barrier against materials passing beneath the container should any of such materials be dropped into the fluid content during removal of a batch.

As will be understood, the use of individual compartments not only enables each batch to be of a size readily manipulable in the washing operation, but also enables the batches to be individual in characteristics. For instance, the quantity may vary in the different compartments, or the materials of one compartment may be fine goods while 90 the material of another compartment be of coarse goods, etc.

Inasmuch as the washing machine is adapted for use in washing other forms of materials in addition to articles of apparel, 95 such as clothing, the words "batch of material" are employed to indicate the contents that may be placed within a compartment for washing purposes.

While I have herein shown and described 100 a preferred embodiment of the invention, it will be readily understood that changes and modifications therein may be found desirable or essential in meeting the various exigencies of use, and I desire to be understood as reserving the right to make any and all such changes or modifications therein as may be found desirable or necessary, in so far as the same may fall within the spirit and scope of the invention as expressed in the 110 accompanying claims when broadly construed.

What I claim is:—

1. A washing machine comprising a casing for the washing fluid, an inner container 115 for the materials to be washed, said container being supported within the casing and having its bottom spaced from the casing bottom, and means for subjecting the material to rubbing action, said means including a plurality of rubbing surfaces movable in planes parallel to each other and operative to divide the container into compartments of constant dimensions to retain the respective compartment contents independent during the washing operation, and means for reciprocating such surfaces in such planes.

2. A washing machine comprising a casing for the washing fluid, an inner container 130

- for the materials to be washed, said container being supported within the casing and having its bottom spaced from the casing bottom, and means for subjecting the material to rubbing action, said means including rubbing surfaces carried by the ends of the container, a plurality of rubbing surfaces between and extending in planes parallel to and spaced from such ends and 10 to each other to produce a plurality of material-receiving compartments, and means operative above the top plane of the casing for reciprocating the intermediate surfaces in their respective planes, said surfaces having 15 an active rubbing length in the direction of reciprocation sufficient to extend into the space between such bottoms when the surfaces are being reciprocated to produce washing action.
- 20 3. A washing machine comprising a fluid receiving casing, a container therein for the materials being washed, said container having a plurality of individual batch-receiving compartments each having opposing walls 25 formed to provide rubbing action on the batch contained within the compartment, said compartments being each of constant dimensions to retain the respective compartment contents independent during the 30 washing operation and being arranged successively in the direction of length of the container, said container having a removable

side wall to permit concurrent access to an end of each of a plurality of compartments.

4. A washing machine comprising a fluid 35 receiving casing, a container therein for the materials being washed, said container having a plurality of individual batch-receiving compartments each having opposing walls 40 formed to provide rubbing action on the batch contained within the compartment, said compartments being arranged successively in the direction of length of the container, said container having a removable side wall to permit concurrent access to an 45 end of each of a plurality of compartments, said container being positioned within the container to provide a space between the removable side and the casing side sufficient to permit removal of container contents 50 through the open end of a compartment produced by removal of the container side, said container having its bottom spaced from the casing bottom, and having a member extending between such bottoms to isolate the 55 space beneath the container in a manner to prevent batch material passing beneath the container while removing a batch.

In testimony whereof I affix my signature in the presence of two witnesses.

MICHAEL BOGRE.
